UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

NEEDLE-BAR-OPERATING MECHANISM.

1,386,323.

Specification of Letters Patent.

Patented Aug. 2, 1921.

Original application filed December 31, 1915, Serial No. 69,644. Divided and this application filed December 17, 1918. Serial No. 267,104.

To all whom it may concern:

Be it known that I, ALBERT H. DE VOE, a citizen of the United States, residing at Westfield, in the county of Union and State 5 of New Jersey, have invented certain new and useful Improvements in Needle-Bar-Operating Mechanisms, of which the following is a specification, reference being had therein to the accompanying drawings.

10 This invention relates to needle-bar operating mechanism for sewing machines and has particular reference to needle-bar mechanism in which the needle-bar may be turned axially as well as reciprocated; the mechanism herein disclosed being particularly useful in embroidering or buttonhole stitching machines having a movable stitch-frame.

15 The invention has for an object to provide a needle-bar operating mechanism of simplified construction which will be strong, durable and efficient in operation.

20 A further object of the invention is to provide a simplified and improved needle-bar mechanism for use in a buttonhole sewing machine having a movable stitch-frame.

25 Further objects of the invention will appear from the following description and claims.

30 The invention preferably comprises a reciprocating needle-bar and a rotary crank disposed at opposite sides of the plane of the work-support; the crank being movable on an axis transverse to the needle-bar; the needle-bar being connected to a reciprocatory 35 stud or slide which, in turn, is connected by a pitman with the rotary crank. In the embodiment of the invention illustrated, the needle-bar is journaled in a rotary and longitudinally slotted bushing and is provided 40 with a spline working in the slot of said bushing so that the needle-bar may be rotated while it is being reciprocated. The slotted bushing is sustained by an arm of a stitch-frame which is movable relative to 45 the main frame of the machine. The rotary crank and its actuating shaft are journaled in the stitch-frame and means are provided for transmitting rotary motion to said shaft while permitting endwise and sidewise movement of the latter with the stitch-frame.

50 In the accompanying drawing, Figure 1 illustrates the preferred construction of needle-bar mechanism as applied to the button-hole sewing machine disclosed in my co-

pending application Serial No. 69,644, filed December 31, 1915, of which this application is a division. Fig. 2 is a cross-section of the needle-bar and needle-actuating bar with their connections. Fig. 3 is a perspective view of certain parts of the latter. Figs. 4 and 5 are respectively a plan and elevation, partly in section, representing the machine bed, the stitching frame and a portion of the feeding mechanism.

55 In the preferred embodiment of the invention, as illustrated, the looper mechanism, as well as the needle mechanism, is mounted in a traveling stitch-frame A mounted in the main-frame of the machine, as disclosed in my said copending application.

60 The stitch-frame A comprises the base-plate 1, having at one end the upwardly extending cylindrical curb or casing 2 for the looper mechanism and rearward thereof the longitudinally extending bearings 3 and 4. 65 The bearing 3 is provided with the bushing 5, and the bearing 4 has slidably fitted within it the tubular bearing boss 6 of a bracket 7 which is formed with a depending fulcrum stud 8 journaled within a suitable 70 bearing aperture in the bed-plate 9 of the main or stationary frame of the machine. The bracket 7 has secured to it by the screw 10 an arm 11 of a bearing sleeve 12 in which is journaled the tubular hub 13 of a bevel 75 pinion 14.

75 The stitch-forming mechanism is driven by means of the crank-shaft 15 which is journaled in the bushing 5 and the bearing boss 6. This shaft passes through the hub 13 80 of the gear 14 and has secured upon its end by the set screw 16 the cross-bar 17 notched in its ends to fit the diametrically opposite and parallel guiding pins 18 formed upon the collar 19 which is secured by means of 85 the set screw 20 upon the gear hub 13 and, with the gear 14, embraces the bearing sleeve 12 to confine the gear against axial movement while the shaft 15 is permitted to move endwise freely. The collar 19 and 90 cross-bar 17 obviously provide a sliding driving connection between the gear-hub 13 and the shaft 15.

95 The bevel pinion 14 is driven by a similar pinion (not shown), carried by a suitable 100 shaft receiving power from the main shaft of the machine, as fully described in my co-pending application.

Rigidly secured in a boss 21, of the base-plate 1 is a standard 22 having secured upon its upper end the hub of an overhanging bracket-arm 23 formed at its free end with a boss 24 in which is secured by a set-screw 25, the depending post 26 with its reduced lower portion entering an apertured bearing boss 27 sustained by the casing 2. Secured upon the post 26 upon opposite sides of the boss 24 are the spaced hubs 28 of the needle-bar frame 29 sustaining the needle mechanism. From the foregoing it will be readily understood that the stitch frame A is free to slide over the base 9 in a direction longitudinally of the shaft 15 and may also swing with the shaft 15 about the fulcrum-stud 8 as an axis.

For the purposes of the present disclosure it is deemed unnecessary to describe the connections with the feed-wheel 30 for imparting to the stitch-frame its traveling or stitch-positioning movements relative to the work as in sewing around a buttonhole. These connections are fully described in my 25 said copending application.

The crank-shaft 15 carries at its forward end the crank-plate 31 formed with the crank-stud 32 which is embraced by a strap 33 at the lower end of a pitman-rod 34 having at its upper end the apertured boss 35 entered by a stud 36 projecting from a split collar 37 which is clamped upon the reciprocating bar 38 journaled in suitable bushings 39 of the needle-frame 29. The pitman 34 is disposed closely in the rear of the casing 2 for the looper mechanism and will also be seen to be mainly in front or forward of the standard 22 and the bracket-arm 23. Secured upon the bar 38 is the split 40 hub at one end of a rigid lateral arm 40 having upon its opposite end a split boss 41 loosely embracing a rotary tubular bushing 42 formed in one side with a longitudinal slot 43 and journaled within bearing 45 bosses of the needle-frame parallel with the bar 38. The bushing 42 is confined against endwise movement by a collar 44 secured thereon below its upper bearing boss and the hub 45 of an inclined crank-arm 46 50 secured thereon above said bearing boss.

Journaled within the bushing 42 is the reciprocating needle-bar 47 carrying at its lower end the needle-clamp 48 in an eccentrically disposed socket of which is secured 55 by a suitable clamp-screw the eye-pointed needle 49. Fitted within the longitudinal slot 43 of the bushing 42 is a spline 50 secured to the needle-bar by screws 51 and provided upon the outer face with projecting lugs 52 embracing between them the collar 41. Through the described connections, the rotation of the crank-stud 32 with the crank-shaft 15 effects the reciprocation of the needle-bar and needle which are caused 60 to turn with the surrounding bushing 42.

As will be observed by reference to Fig. 1, the connections between the intermediate bar 38 and the needle-bar and the pitman-rod, respectively, are upon opposite sides of the intermediate bar and extend laterally to such extent that a sufficient clearance is provided between the needle and the pitman-rod to accommodate the margin of the work in which the buttonholes are formed.

The work is held in suitable clamps, such as disclosed in my said copending application, and is supported at the stitching point by the usual throat-plate or button 43 fixedly mounted on the rotary turret 44 which is journaled within the casing 2.

Having thus set forth the nature of the invention, what I claim herein is—

1. In a sewing machine, in combination, a work-support, a needle-bar sustained at one side of the work-support and carrying a needle, a rotary crank disposed at the opposite side of the work-support and movable on an axis transverse to said needle-bar, a stud with which the needle-bar is connected and with which it performs reciprocatory movements in unison, and a pitman connected at its opposite ends to said crank and said stud and between its ends being free of connection with moving parts of the machine.

2. In a sewing machine, in combination, a work-support, a needle-bar sustained at one side of the work-support and carrying a needle, a reciprocating bar disposed laterally of and parallel with the needle-bar and at the same side of the work-support, a lateral stud and an oppositely projecting rigid arm carried by said reciprocating bar, the latter affording a driving connection with the needle-bar, a rotary crank disposed at the opposite side of the work-support and movable on an axle transverse to said bars, and a pitman connection between said crank and said stud.

3. In a sewing machine, in combination, a work-support, a needle-bar sustained at one side of the work-support and carrying a needle, a rotary and longitudinally slotted bushing in which said needle-bar is journaled to reciprocate, a spline upon the needle-bar working in the slot of said bushing and provided exterior to the latter with longitudinally spaced lugs, a reciprocating bar journaled in fixed bearings and disposed parallel with the needle-bar, a lateral stud and an oppositely projecting rigid arm carried by said reciprocating bar, the outer portion of the latter being embraced by the spaced lugs of the needle-bar spline, a rotary crank disposed at the opposite side of the work-support and movable on an axis transverse to said bars, and a pitman connection between said crank and said stud.

4. In a sewing machine, in combination, a main frame, a stitch-frame movable relatively to the main frame and comprising a

- base-portion and an overhanging bracket-arm, a driving shaft journaled in said base-portion, a crank on said shaft, a needle-bar journaled for reciprocation and rotation in 5 said bracket-arm, an intermediate element connected for up and down movement in unison with the reciprocation of said needle-bar, and a pitman connection between said crank and intermediate element.
- 10 5. In a sewing machine, in combination, a main frame, a stitch-frame movable relative to the main frame and comprising a base portion, an overhanging bracket-arm and a head carried at the free end of the 15 bracket-arm, a driving shaft journaled in said base portion, a crank on said shaft, a needle-bar journaled for reciprocation and rotation in said head, an intermediate element located at the free end of the bracket- 20 arm for up and down movement in unison with the reciprocations of the needle-bar, and a pitman connection between said crank and intermediate element, said pitman con-

nexion being disposed forward of said bracket-arm. 25

6. In a sewing machine, in combination, a main frame, a stitch frame movable relative to said main frame and comprising a base portion, a standard and an overhanging bracket-arm carried by said standard, 30 a driving shaft journaled in said base-portion, a crank on said shaft disposed forwardly of said standard, a head carried at the free end of said bracket-arm, a needle-bar journaled for reciprocation and rotation 35 in said head, an intermediate element located substantially at the free end of the bracket-arm and connected to the needle-bar for movement in unison with the latter, and a pitman connection forward of said 40 standard between said crank and intermediate element.

In testimony whereof I have signed my name to this specification.

ALBERT H. DE VOE.
